United States Patent [19]

Lenson

[11] Patent Number: Des. 302,313

[45] Date of Patent: ** Jul. 18, 1989

[54] EROSION CONTROL DEVICE

[76] Inventor: **Walter J. Lenson**, 140 Millbank Drive, London, Ontario, Canada, N6C 4V7

[**] Term: 14 Years

[21] Appl. No.: 937,524

[22] Filed: Nov. 28, 1986

[30] Foreign Application Priority Data

May 27, 1986 [CA] Canada 27-05-86-4

[52] U.S. Cl. D25/117; D25/113

[57] CLAIM

The ornamental design for an erosion control device, as shown.

DESCRIPTION

FIG. 1 is a downward front perspective view of a erosion control device embodying my design.

FIG. 2 is an upward rear perspective view of the erosion control device illustrated in FIG. 1.

FIG. 3 is a top plan view of the erosion control device illustrated in FIG. 1.

FIG. 4 is a front elevational view of the erosion control device illustrated in FIG. 1.

FIG. 3

FIG. 4
